CLAMP FOR DROP WIRE BARS

Sherwood O. Dodge, Medford, and Herman J. Malafey, Brighton, Mass., assignors to H. F. Livermore Co., Allston, Mass., a corporation of Massachusetts

Application April 13, 1934, Serial No. 720,398

6 Claims. (Cl. 139—358)

This invention relates to an improved clamp for the drop wire bars of a loom.

In certain types of looms it is customary to provide the drop wire bars, with which said looms are equipped, with one or more brackets as may be required to prevent said bars from spreading and sagging. To this end the brackets are provided with slots into which the lower portion of the bars project. Normally the lower edge of the bars contact with the bottom of the slots, but there is a narrow space provided between the sides of the bars and the sides of the slots. When the loom is in operation the drop wire bars vibrate continually with the result that both the bars and brackets are subjected to excessive wear and it is necessary that they be replaced frequently.

The object therefore of this invention is to embody in the structure of the brackets that are provided for holding the drop wire bars, a clamping mechanism which will effectively eliminate the vibration of the bars and thereby reduce the noise and wear usually occasioned by the continual vibrating contact of the bars with the brackets.

The invention consists in an improved clamping mechanism for the drop wire bars of a loom as set forth in the following specification and particularly pointed out in the claims thereof.

Referring to the drawing:—

Fig. 1 is a plan view of the clamp mechanism of this invention, together with portions of the drop wire bars for which the clamp is provided.

Fig. 2 is a vertical sectional elevation of the clamp and associated parts illustrated in Fig. 1, together with a pair of warp threads and the drop wires therefor.

Fig. 3 is an end view of the clamp mechanism as viewed from the right of Fig. 2.

Like numerals refer to like parts throughout the several views of the drawing.

In the drawing, 5 and 6 represent the front and rear drop wire box plates respectively of a loom, 7 the drop wire bars and 8 a separator rod which constitutes a support for the warp threads. These members are all old and well known in the art and extend from one side of the loom to the other.

Mounted upon the box plates 5 and 6 is a bracket 9 which constitutes a brace and support for the drop wire bars 7. The bracket 9 may be secured to either one or both of the box plates as may be desired and any suitable number of said brackets may be provided as may be required to support the drop wire bars, said num-

ber being determined by the width of the loom. In the present instance the bracket 9 is adjustably secured to the box plate 5 by an angle member 10 and bolt 11.

The drop wire bars 7 are located in slots 12 provided in the bracket 9, said slots extending downwardly from the top edge of the bracket and the lower edge of the bar being seated at the bottom of the slot, but preferably there is a very narrow space provided between the sides 13 of the bar and the sides of the slots. In the present instance there are two drop wire bars 7 illustrated, but a third slot 12 is provided in the bracket 9 to receive a third drop wire bar which is provided in certain looms, and still other slots 14 and bars may be provided if it is so desired without departing from the spirit of this invention.

Drop wires 15 well known in the art and for which the bars 7 are provided are illustrated in Fig. 2. These drop wires are provided with slots 16 to receive the bars 7 and holes 17 to receive the warp threads 18 of the loom.

A separator rod 8 is located at the bottom of a slot 17 also provided in the bracket 9 and projecting downwardly from the top edge thereof.

Pivottally attached at 18 to the bracket 9 is a bowed tension member 19 constructed of resilient spring metal. The tension member extends lengthwise of the bracket 9, a short distance above the top edge thereof and just above the upper edges of the drop wire bars 7. Secured to the under side of the tension member 19 and in effect forming a part thereof is a cushion 20 formed of a suitable compressible material such, for example, as rubber or leather. When the tension member 19 is depressed the cushion 20 thereof is adapted to engage the top edges of the bars 7. The tension member 19 is held depressed and flexed under tension by means of a latch 21 which is mounted at the free end portion 22 of the tension member 19. The latch 21 projects through a hole 23 provided in the tension member, said hole being somewhat larger in diameter than the diameter of the rod from which the latch is formed, thereby permitting said latch 21 to swing freely upon the tension member. The lower portion of the latch 21 is bent at 24 to form a hook portion which is adapted to interlock with a notch 25 provided upon the lower edge of the bracket 9. A nut 26 has screw-threaded engagement with the upper end portion of the latch 21 and is utilized as a means for placing a tension upon the tension member 19 and forcing the cushion 20 carried thereby into engagement with the upper edges of the drop wire bars 7 in a man-

ner to compress the cushion 20 during said engagement.

A clamping device of this invention may be secured at intervals to the box plates 5 and 6 to provide an effective means for clamping the drop wire bars 7 between the cushion 20 and the brackets 9 thereby preventing these bars from vibrating with the consequent wear to both the bars 7 and brackets 9. It is evident that any desired tension may be applied to the tension member 19 by manipulating the adjusting nut 25, and the compression of the cushion 20 will vary according to the pressure placed upon the tension member by the nut 25.

It will be noted that in this device the tension member 19 may be lifted to relieve the pressure upon the bars 7 as may be required when repairs or replacements are necessary and the tension member can be swung backwardly into a position which will not interfere with the bars 7 or drop wires 13. During this movement of the tension member the latch 21 will remain securely attached to the tension member.

We claim:

1. A clamp comprising, in combination, a bracket provided with slots therein to receive the drop wire bars of a loom, a resilient tension member embodying therein a bowed spring pivotally attached to said bracket, and means to hold said tension member flexed and in yielding engagement with said bars.

2. A clamp comprising, in combination, a bracket provided with slots therein to receive the drop wire bars of a loom, a resilient downwardly bowed tension member pivotally attached to said bracket and adapted to be sprung toward said drop wire bars, and means to hold said tension

member yieldingly depressed in engagement with said bars.

3. A clamp comprising, in combination, a bracket provided with slots therein to receive the drop wire bars of a loom, a tension member mounted upon said bracket, a cushion for said tension member, and means to hold said tension member depressed with said cushion in engagement with said bars.

4. A clamp comprising, in combination, a bracket provided with slots therein to receive the drop wire bars of a loom, a resilient tension member pivotally attached to said bracket, a cushion for said tension member and adapted to flex in unison therewith, and means to hold said cushion compressed in engagement with said bars.

5. A clamp comprising, in combination, a bracket provided with slots therein to receive the drop wire bars of a loom, a resilient tension member pivotally attached to said bracket, a cushion fast to said tension member and adapted to flex in unison therewith, means to hold said cushion compressed in engagement with said bars, and means to vary the pressure applied to said bars.

6. A clamp comprising, in combination, a bracket provided with slots therein to receive the drop wire bars of a loom, a resilient tension member pivotally attached at one end thereof to said bracket, a cushion carried by said tension member, a latch mounted to swing at the free end of the tension member and adapted to be sprung into locking engagement with said bracket and hold said cushion compressed in engagement with said bars, and means upon said latch to vary the pressure applied by the cushion to said bars.
